(57) **CLAIM**

An ornamental design for a lanyard slider with dual pen holders, as shown and described.

DESCRIPTION

FIG. 1 is a right-side, top, and front perspective view of a lanyard slider with dual pen holders showing our new design; FIG. 2 is a front elevational view thereof; FIG. 3 is a top plan view thereof; FIG. 4 is a bottom plan view thereof; FIG. 5 is a rear elevational view thereof; FIG. 6 is a side elevational view thereof; and, FIG. 7 is right-side, front, and top perspective view thereof showing the lanyard slider with dual pen holders in use with writing implements and a lanyard cord, where the objects shown in broken lines are shown for the purpose of illustrating environment and form no part of the claimed design.
